Letter Patent No. 2341, dated June 26, 1866

Design for a Trade Mark

The schedule referred to in these Letters Patent, accompanying, part of the same

To all whom it may concern.

Be it Known that we A. J. Sohl Levi Sohl and David Gibson of Indianapolis in the County of Marion and State of Indiana, have invented a New and Improved "Trade Mark" and do hereby declare that the following is a full clear and exact description thereof, which will enable others skilled in the art to fully understand and practice the same.

The present invention relates to a new and useful Trade Mark for the Marketing of barrels, bags or other articles containing flour, which trade mark is placed upon the barrel or bag, by the ordinary mode of stencilling or in any other proper Manner.

This trade mark consists of a wreath or circle of leaves a in the centre of which is a representation of the letter A of a size equal to the diameter of the wreath or nearly so, having the figure of a rose B, and its stem C and leaves D, marked upon the upper portion of the letter A. The brands of the flour such as "La Rosa Blanche" or "White Rose" surrounds the inside of the upper portion of the circle or beneath a and the name of the business firm manufacturing such flour, around the inside of the lower portion of the circle as plainly represented in the plates accompanying this description, as well as all the other portions of the design for the trade mark herein explained.
